UNITED STATES PATENT OFFICE.

MARIUS SAUVAGEON, OF PARIS, FRANCE.

ELECTRIC FURNACE.

Application filed April 2, 1921. Serial No. 458,018.

To all whom it may concern:

Be it known that I, MARIUS SAUVAGEON, a citizen of the French Republic, residing at No. 7 Rue de Petrograd, Paris, France, have 5 invented certain new and useful Improvements Relating to Electric Furnaces (for which I have filed applications in France August 3, 1916; Canada, June 6, 1919; Italy, May 2, 1919), of which the following is a 10 specification.

This invention relates to an electric resistance furnace heating by radiation either from the crown alone, from the sides alone or simultaneously from the crown and from 15 the sides. The heat is produced by the passage of current through an electric resistance formed partly by material in grains having a basis of carbon placed in chambers disposed one beside the other above the crown 20 of the furnace or in the walls thereof and partly by the crown and the walls themselves which are constructed of special material being good conductors of heat and becoming electric conductors at high temperature. The 25 heating chambers in which is placed the resistance material in the form of grains have openings at their upper ends in such manner as to permit the inspection of the chambers and especially to assure the automatic 30 replacement of the granular resistance material which is used so as to maintain always the same conditions in the apparatus in assuring a constant section of the resistance material and thus the permanence of the 35 conditions of working, that is to say the automatic feed of the granular resistance material.

This mode of heating by radiation may be 40 applied to various industrial furnaces adapted for the fusion, heating or baking of substances and at any temperature from the lowest such as required in stoves to the highest such as is necessary in the manufacture of steel, of glass and ceramic products. In 45 each case the laboratory or bed of the furnace will be provided of a form and dimensions according to the manufacture to be carried on.

The accompanying drawings define the 50 object of the invention and indicate by way of example three modes of construction of furnace.

Figure 1 is a transverse section of a fur-

nace heating from the crown alone with horizontal electrodes for the current and 55 destined for operations of heating or baking of materials placed directly upon the hearth.

Figure 2 is a longitudinal section of the furnace represented in Figure 1 one part of which is made through the feeding pockets 60 and the other between the feeding pockets.

Figure 3 is a transverse section of a furnace similar to that indicated in Figures 1 and 2 but with the crown and electric hearth suspended and an independent bed provided 65 especially for fusion of products at high temperature such as steel and glass.

Figure 4 is a longitudinal section of the furnace represented in Figure 3, the section being taken partly through the feeding 70 pockets and partly between the pockets.

Figure 5 is a transverse section of a furnace simultaneously heating from the crown and walls with vertical electrodes placed beneath destined to heat the solid or melted 75 substances contained in the receptacle.

Figure 6 is a longitudinal section of the furnace represented in Figure 5, the section being taken partly through the axis of the furnace and partly through the electrodes. 80

Figures 7 and 8 show respectively in longitudinal section and horizontal section a modification permitting the application to the case of a furnace having an oscillating crucible of heating chambers with an auto- 85

matic feed. The furnace represented in Figures 1 and 2 comprises a laboratory 1, a bed 2, walls 3, a crown 4 and a working hole 5 closed by a door 6. The mode of construction of the 90 bottom and walls as well as the position and number of the working holes are provided in each case according to the heating operation to be carried out and the nature of the products to be treated.

The crown 4 and the walls of the electric hearths are made of very refractory material constituted by ferrite of magnesia and ferrite of alumina containing from 5 to 10 per cent of oxide of iron agglomerated in a press 100 and heated to a high temperature. These materials have the property of being good conductors of heat and of becoming good conductors of electricity at high temperatures and have a high physical resistance. 105 The construction of the setting is effected in

the usual manner by the employment of bricks or of blocks of convenient form and a grouting of the same substance as the bricks or blocks is employed for the joints.

- 5 Above the crown are disposed a series of heating chambers 7 having a length extending across the crown and separated one from the other by partitions 8. They are closed at their upper parts by a top in which are 10 provided several openings 9 having the form of pockets widening out downwardly. These openings are closed normally by cover plates 10. At the two opposed extremities of each chamber electrodes 11 are provided connected by the conductors 12 to the leads 13. These electrodes are placed horizontally or vertically and the chambers can be disposed either parallel or in series or in series and parallel. Further the heating chambers can 15 20 extend either across the furnace or longitudinally of the furnace.

The furnace is braced as usual as for example in the manner illustrated by means of bars, braces and bolts. In each chamber 25 there is charged an electric conductive substance in the form of grains. For this purpose natural or artificial graphites may be employed retort carbon, coke and the like. The size of the grains as well as the section 30 of each chamber may be determined according to the nature of the operation to be performed. The resistance material fills each chamber as well as the feeding pockets 9 as indicated in the drawing. It follows that if 35 part of the substance burns it is replaced automatically by the excess contained in the feeding pockets and thus the section of the resistance material remains always the same. As before indicated there is obtained by 40 this means a furnace which has practically a constant working. Moreover each chamber can be inspected and cleared easily even in working through the feeding pockets.

The furnace represented in Figures 3 and 45 4 is similar to the furnace previously described with respect to the disposition of the heating crown and the electric hearths but the whole is entirely suspended and separated from the hearth. The latter disposed beneath is constituted by a basin destined to receive the substance to be treated. The space comprised between the suspended crown and the basin forms the laboratory 1 which is closed by the bricks placed upon 50 55 the grouting at the edges of the basin.

The apparatus thus comprises essentially a lower structure constituted by a basin 2' resting upon a series of partitions 3' permitting the free passage of air beneath. 60 This basin is provided with a tapping channel 14 where the product is to run from the basin.

The superstructure is constituted by a ledge 15 resting upon angle irons 15' and 65 pillars 16 connected to the furnace braces

and serving to support the whole. In one of the vertical walls is provided a charging aperture 5 closed by a door 6. Upon the ledges 15 rests the crown 4. Above the crown are disposed the heating chambers 7 70 separated by partitions 8 and closed by a top in which are provided the feeding pockets 9 closed by the covers 10. At the two extremities of each heating chamber are provided the electrodes 11 connected by conductors to the conducting bars 13.

The crown and the walls of the electric hearths are provided as in the construction previously described from highly refractory material being heat conductors and good 80 electric conductors at high temperature and formed with a base of ferrite of magnesia or of ferrite of alumina. In each chamber the resistance in grains is charged as described in the first modification and in the 85 same manner. Each chamber is filled as well as the feeding pockets whereby constant working is ensured as well as the inspection and clearing of the heating chambers.

The disposition of the furnace represented in Figures 5 and 6 is similar to that of furnaces which have been described but the heating instead of operating through the crown alone is effected through the crown 90 and walls combined in such manner that in this case the heating chambers entirely cover the laboratory, their section which is indicated in Figure 5 following the general form of an inverted U. The apparatus comprises 95 a laboratory 1, a bottom 2, interior walls 3, a crown 4, exterior walls 3'' and a working hole closed by a door 6. The front face 3, the crown 4 and the walls of the electric hearths are made of material having a basis 100 of ferrite of magnesia as previously referred to. Between the two walls 3 and 3'' and above the crown 4 are disposed a series of heating chambers 7 separated one from the other by partitions 8. They are closed at 110 their upper parts by a top in which is provided a number of feeding chambers 9. At the lower extremities of each chamber electrodes 11 are provided connected by the conductors 12 to the bars 13.

In each chamber the resistance material in grains is fed in the manner previously indicated and in the same way. The material fills each chamber and the feeding pockets and permits for the reasons above stated a constant working and of permitting the inspection and clearing of the heating chambers.

One may also employ a furnace in which the heating is effected only through the 125 walls. In such a case the heating chambers will be connected two by two in each wall with communication at their upper ends with the feeding pockets.

Figures 7 and 8 show a modification of 130

urnace with an oscillating crucible. As will be seen from Figures 7 and 8 the furnace supported by the pivoting axes 17 mounted on the pillars 18 comprises a crucible 19 mounted in the laboratory 1. From each side of the laboratory feeding pockets 9 are provided separated by partitions 8. The resistance material feeds these pockets and rests upon the electrodes 11 disposed 10 at the base of each of the heating chambers from which the pockets extend. The oscillating crucible is thus flanked with two layers of resistance material having each the general form of a U whose branches will be 15 seen in Figure 8 at 7^a and 7^b.

Thus in the different types of heated furnace according to the invention the heating chambers can be disposed in the longitudinal direction as well as transversely. In 20 such a case numerous chambers may be provided above the crown but only one is provided in the walls so as to be able to dispose them easily with their feeding pockets.

The operation of the electric resistance 25 furnace heating by radiation in the manner described is as follows:

On the current passing through the granular resistance material there is a transformation of the electric energy into heat. 30 The resistance material as well as the walls of the chamber ensure this heat and take a temperature according to the quantity of heat evolved. This is transmitted then in 35 part by conductivity and radiation across the crown or the walls and raises the temperature of the laboratory of the furnace as well as of the substances contained therein which are to be treated, the other part being lost in the atmosphere by conductivity 40 and radiation from the exterior walls.

If the furnace operates at a high temperature the material constituting the crown becomes in such a case a good conductor of electricity and it follows that a part of the 45 current passes through the granular resistance material and the other part through the crown or the walls. The heat thus evolved closer to the furnace has its transformation facilitated and thus the ther-

mal efficiency of the furnace is increased. 50 What I claim is:—

1. An electric furnace, comprising a hearth the crown wall of which is formed of material which is a good conductor of heat and at high temperatures a good conductor of electricity, a series of heating chambers above said crown wall, granular resistance material filling said heating chambers, and electrodes extending into said chambers and contacting with said granular 55 material.

2. An electric furnace, comprising a hearth the crown wall of which is formed of material which is a good conductor of heat and at high temperatures a good conductor 65 of electricity, a series of heating chambers above said crown wall, feeding pockets forming continuations of said chambers and opening at the top of said furnace, granular resistance material filling said chambers 70 and pockets, and electrodes extending into said chambers and contacting with said granular material.

3. An electric furnace comprising a hearth the side and crown walls of which 75 are formed of material which is a good conductor of heat and at high temperatures a good conductor of electricity, inverted U-shaped heating chambers extending vertically along said side walls and horizontally 80 over the crown walls, granular resistance material filling said chambers, and electrodes extending into the lower ends of the vertical branches of the heating chambers and contacting with said granular material. 85

4. An electric furnace comprising a hearth the crown and side walls of which are formed of material consisting of ferrite of magnesia and ferrite of alumina containing from five to ten per cent of oxide of iron, a heating chamber disposed at the outside of certain of said walls, granular resistance material filling said heating chamber, and electrodes extending into said chamber and contacting with said granular material. 90 95

In testimony whereof I have signed this specification.

MARIUS SAUVAGEON.
